HOLDER ARM FOR DOORS

Henry G. Voight, New Haven, Conn., assignor to
Sargent & Company, New Haven, Conn., a corporation of Connecticut

Application February 23, 1932, Serial No. 594,567

15 Claims. (Cl. 189—49)

This invention relates to holder arms for doors and more particularly to a type of arm ordinarily used in connection with a so-called door check, which serves to move a door to closed position and to check such movement near the end thereof so that the door will close softly. Such devices are many times provided with means by which the door may be held open in a given position, and in some installations it is desirable that a door having such means be also arranged that it may automatically close in case of fire.

Such an arrangement is provided in the present invention by having a fusible member arranged as one of the elements holding the door in open position so that when the fusible member is subjected to heat and is rendered ineffectual, the door will be released and be allowed to close under the influence of the closing mechanism.

One object of the invention, therefore, is to provide the holder arms of a door check with means to hold the door in a desired open position, which means will be rendered ineffective when subjected to heat so as to permit the door to close in case of fire.

A further object of the invention is the provision of holder arms for a door check structure such that the door may be held open in a desired position, the mechanism for holding the door open including a fusible member which will be destroyed by heat so that the door will be permitted to close.

A still further object of the invention is to provide in a simple and economical structure, a door check holder arm structure which will hold the door in open position but which will release the door and permit the closing thereof in case of fire.

To these and other ends, the invention consists in the novel features and combinations of parts to be hereinafter described and claimed.

In the accompanying drawings:

Fig. 1 is a top plan view of a door check holder arm structure applied to a door and embodying my invention;

Fig. 2 is an enlarged top plan view of the pivot joint between the holder arms;

Fig. 3 is a side elevational view of the parts shown in Fig. 2;

Fig. 4 is a section on line 4—4 of Fig. 2;

Fig. 5 shows a perspective view of one of the holder arms;

Fig. 6 is a perspective view of one of the members for holding the door in open position;

Fig. 7 is a view of the pivot bolt connecting the arms, and

Fig. 8 is a view similar to Fig. 2 showing a somewhat modified form of the invention.

To illustrate a preferred embodiment of my invention, I have shown a door casing 10, to which is hinged a door 11, having applied thereto a door check and closure mechanism 12. Through the upper end of the casing of the mechanism 12, extends a non-circular shaft 13, in the usual form, to which is secured one of the arms or links 14 of the holder arm. The other arm or link 15 is pivoted to the arm 14 by the pivot bolt 16, which will be more fully described hereinafter. The arm 15 is connected to the door casing 10 by means of the usual adjustable link structure 17.

As shown more especially in Fig. 4, the joint between the arms 14 and 15 comprises three members, a flat head portion 18 in which the arm 14 terminates, a washer-like member 19, and a ring 20, which, as shown in Fig. 5, is formed at the end of the arm 15. The washer-like element 19 is provided at its central portion with an upstanding boss 21, having a square opening 22 therethrough, the opening extending also through the body portion of the washer. This member is also provided with a lug or projecting arm portion 23 within which is formed a notch 24. The members 18 and 19 constitute friction heads which will bind together to hold the door in a predetermined open position.

The head 18 of the arm 14 is provided with a threaded opening which threadedly receives the lower threaded end 25 of the pivot bolt 16. The intermediate portion of this bolt, above the threaded end 25, is non-circular or square in cross-section, as shown at 26, while the upper portion of the bolt is circular and threaded as at 27. After the bolt has been threaded in the opening in the head 18, the washer-like member 19 is placed on the bolt, as shown in Fig. 4, the squared portion 26 of the bolt being received in the square opening 22 in the boss 21.

The ring-like member 20 at the end of the arm 15, is provided with an opening 28, which is adapted to be placed over the boss 21, the opening being of such size as to receive the boss therein so that the arm 15 will be pivoted about the boss or about the axis of the bolt 16. The ring-like member 20 is also provided with a peg-like portion 29, and the arm 15 is provided with spaced ears 30 and 31, having registering openings 32 and 33 therein.

After the member 19 has been placed upon the pivot bolt 16, and the member 20 is mounted on the member 19, a washer 34 is placed upon the pivot bolt and above the boss 21 and ring-like

- member 20, and held in place by the adjusting nut 35. The height of the boss 21 should be at least equal to the thickness of the ring-like member 20, so that the latter will not be clamped between the member 19 and the washer 34.
- 5 A lever 36 is pivoted to the ears 30 and 31 by means of the pivot pin 37 passing through the openings 32 and 33, this lever having a detent 38 which engages in the recess 24 of the member 19.
- 10 The lever is held in this position by the fusible link 39, secured at one end to the end of the lever by the screw 40, and having its other end engaging the pin or peg 29. The detent 38 and recess 24 are so shaped that when the fusible link is rendered ineffective and the end of the lever 36 is released, a rotating force applied to the arm 15 will withdraw the detent from the recess and thus release the arm 15 from the member 19 and permit the arm to swing about the boss 21.
- 15 20 It will be understood that ordinarily the arm 15 and the element 19 are locked rigidly together by the lever 36, and the fusible link 39, and that when the door is opened there will be relative movement between the arms 14 and 15 about the pivot bolt 16, and, therefore, relative movement between the arm 14 and the member 19. As the pivot bolt 16 is non-rotatably secured to the member 19, the opening of the door will result in the head portion 18 of the arm 14 being screwed 25 upwardly on the threaded portion 25 of the pivot bolt until the upper surface of the head frictionally engages the lower flat surface of the element 19 to bind the two parts together and hold the door open. The position at which the door 30 will be held open in this manner may be varied by adjustment of the nut 35, so that the head 18 will have to be moved a greater or less distance along the pivot bolt before it is frictionally engaged with the element 19.
- 35 40 If, when the door is held in open position by the frictional engagement described, the fusible link should be subjected to sufficient heat to render it ineffective, the end of the lever 36 would be free and the spring pressure applied to the arms 14 and 15 by the door closer will result in throwing the detent 38 out of engagement with the recess 24, so that the arm 15 and member 19 are no longer locked together and the arm 15 will be free to turn about the boss 21, although the member 19 will still be frictionally locked to the head 18. This will, of course, permit the door to close in exactly the same manner as though the frictional engagement was released.
- 45 50 In Fig. 8 of the drawings I have shown a slightly modified form of my invention. This modification is the same as that shown in Figs. 1 to 7 of the drawings, with the exception of the lever 36^a. This lever instead of having an opening to receive the pin passing through the ears 31 is provided with a hooked end 41, which merely hooks around the body of the pin 37. The lever 36^a is, therefore, not pivoted to the arm 15, but is detachably engaged with the pin and held in this position by the fusible link 39, which engages the end of the lever 36^a and engages the pin 29 on the end of the arm 15. In this instance, when the fusible link gives way, the detent 38 will be forced out of the recess 24, all as heretofore described, and the lever 36^a being merely engaged with the pin 37 will fall to the floor immediately releasing the arm 15. In other respects, the arrangement shown in Fig. 8 is substantially like that shown in Figs. 1 to 7 of the drawings.
- 55 60 While I have shown and described a preferred embodiment of my invention, it will be under-

stood that it is not to be limited to the details shown but is capable of modification and variation within the spirit of the invention and the scope of the appended claims.

What I claim is:

1. A door closer comprising an arm having an opening at one end, and a pivot member in said opening, a pair of members pivoted to said arm about said pivot member, one of said members being secured to the other by a fusible link and constituting a second arm of the door holder, and means for releasably securing the other of said members to the first arm to hold said parts at a predetermined angular position, said means being independent of said fusible link.

to said bolt and having an upstanding boss surrounding the bolt, a second arm rotatably engaged with said boss, and means normally securing said second arm against rotation about said boss, said means comprising a lever engaging said arm and member, and a fusible link holding said lever in place.

9. A door holder device comprising an arm, and a pair of elements coincidentally pivoted to 10 said arm, one of said elements comprising a member adapted to be frictionally secured to the arm, and another of said elements constituting a second arm of the holding device and means for securing said last named element to said 15 first element by a member adapted to be incapacitated by heat, and independently of said frictional securing means.

10. A door holding device comprising a pair of arms adapted to be pivotally secured together at 20 one end thereof, a washer-like member positioned at the pivoted ends of said arms, a pivot bolt for connecting the two arms and the washer-like member together, means adapted to be incapacitated by heat for securing one of said arms 25 to said washer-like member, and means for frictionally securing said washer-like member to the other of said arms upon relative angular movement of said arms.

11. In a mechanical door holder and closer, 30 closer mechanism including a link, two arms each pivotally connected to said link, said arms being capable of independent rotative movement under one condition, holding means to prevent said independent rotative movement under another condition, said means including a fusible device 35 which when ruptured releases said holding means to permit movement of one of said arms relatively to the other to close the door.

12. In a door closer and holder, two relatively 40 rotatable friction heads, means to cause said heads to be frictionally connected on the one hand and disconnected on the other hand, said means comprising two arms, one of said arms being rigidly connected to one of said heads, the

other arm being rotatably mounted on the other head, locking means when in locking position preventing the last-mentioned arm from rotating on said last-mentioned head and when in its unlocking position freeing said parts to permit them to turn relatively to each other, and a fuse to hold said locking means in its locking position while said fuse is intact.

13. In a door holder and closer, closer mechanism including a link, two arms each pivotally 10 connected to said link, said arms being capable of independent rotative movement under one condition, holding means to prevent said independent rotative movement under another condition, said means including a member pivoted to one of 15 said arms and engaged with the other thereof, and a fusible link for holding said member in operative position.

14. In a door holder and closer, a closer arm, 20 a link, a friction head at one end of said closer arm, a second friction head, a screw connection between said heads to move the same toward and away from each other for frictional engagement and disengagement, a pivotal connection between the link and said second friction head, means 25 to lock said link to said second friction head to prevent relative turning movement between said parts, and a fusible device to release said lock in case of fire to permit the closer to shut the door.

15. In a door holder and closer, a pair of pivoted members comprising a closer arm and a link, a friction head at one end of one of said members, a second friction head, a screw connection between said heads to move the same toward and 35 away from each other for frictional engagement and disengagement, a pivotal connection between the other of said members and said second friction head, means to lock said pivotal connection against movement to prevent relative turning 40 movement between said parts, and a fusible device to release said lock in case of fire to permit the closer to shut the door.

HENRY G. VOIGHT.
